EX

OR D 20,045

DESIGN.

J. L. GOBEILLE.
COOKING RANGE.

Patented July 22, 1890.

No. 20,045.

UNITED STATES PATENT OFFICE.

JOSEPH LEON GOBEILLE, OF CLEVELAND, OHIO, ASSIGNOR TO J. S. & M. PECKHAM, OF UTICA, NEW YORK.

DESIGN FOR A COOKING-RANGE.

SPECIFICATION forming part of Design No. 20,045, dated July 22, 1890.

Application filed June 3, 1890. Serial No. 354,173. Term of patent 7 years.

To all whom it may concern:

Be it known that I, JOSEPH LEON GOBEILLE, a citizen of the United States, residing at Cleveland, in the county of Cuyahoga and State of Ohio, have invented and produced a new and original Design for Cooking Ranges, of which the following is a specification, reference being had to the accompanying photograph, forming a part thereof, which illustrates a cooking-range embodying the design.

The design is a figure having a rectangularly-shaped top A and a rectangular main body B, from the ends of which extend rectangular figures A' and B', the bottom of one of which figures A' is downwardly and inwardly curved, and the bottom of the other figure B' is likewise curved, but in an opposite direction. The main body figure terminates at its bottom in an ogee-like border a,

which merges into the curved upper lines of a rectangular base figure D, the outer face of which figures appear to curve upward, and pendent leg-like figures d appear at the corners of the base figure. A lattice shelf-like figure E appears to join with the main body B and extend over the ogee-like border a and base figure D.

I claim—

In a design for a range herein shown and described, the main rectangular body figures, the base figures, and the end figures, the bottoms of which are curved downward and inward to the body figure, as specified.

JOSEPH LEON GOBEILLE.
